ATTORNEYS.

UNITED STATES PATENT OFFICE.

CHARLES HUFF, OF ST. LOUIS, MISSOURI.

PACKAGE AND BOOK HOLDER.

SPECIFICATION forming part of Letters Patent No. 300,979, dated June 24, 1884.

Application filed April 7, 1884. (No model.)

To all whom it may concern:

Be it known that I, CHARLES HUFF, a citizen of the United States, residing at St. Louis and State of Missouri, have invented certain new and useful Improvements in Package and Book Holders, of which the following is a description.

The drawing represents a perspective view of my package and book holder.

10 My invention relates to improvements in package and book carriers; and it consists in the peculiar construction and arrangement of the parts, as hereinafter more fully set forth, and pointed out in the claims.

15 Referring to the drawing, A represents a right-angular frame formed of a single piece of wire, and consisting of the parallel horizontal arms a, provided with loops b at their outer ends and bent-up vertical arms c at their opposite ends, joined together at their upper ends by the bent horizontal arm d, the arms c and d forming three sides of a rectangle, and constituting, with the horizontal arms a, the main frame of the carrier, formed of a single 25 piece of wire bent into the shape described. The horizontal arms a of the right-angular frame A are connected together by means of wire rods e at right angles to the parallel horizontal arms a and diagonal wire rods h, said 30 wire rods serving the double purpose of tying the horizontal arms a together and preventing the escape of any matter in the package at the bottom of the frame A, or small books passing through the space between the horizontal 35 arms a.

B represents a spring-frame made of a single piece of wire, forming three sides of a rectangle, and provided with hooks i i at the lower ends of the longitudinal sides g g of the spring-frame B, which engage with the loops b at the outer ends of the horizontal arms a. The upper end, k, of the rectangular frame B is formed by bending the wire constituting the frame B at the upper ends of its longitudinal sides g g.

40 The upper horizontal part, k, of the rectangular spring-frame B is provided with a bent-up loop, l, for engaging with a rack in the handle, hereinafter more fully described. The spring-frame B has its longitudinal sides g g convexed 45 or curved inwardly, and is provided with one or more cross-pieces, m, each beveled on its

inner face, and provided with staples or eye-bolts n, secured to the cross-piece m near its ends, and passing around the longitudinal arms g of the spring-frame B, by means of which 55 construction the cross-piece m can be adjusted or slid up and down on the arms g g, so as to grasp packages or books inserted in the carrier. Similarly-constructed adjustable cross-bars m may also be applied to the vertical arms 60 e e of the right-angular frame A. The handle C of the carrier, which is pivoted to the horizontal arm d of the main right-angular frame A, is formed of a single piece of wire, D, and is constructed as follows: One end o of the wire 65 D is provided with a hook, o', at one end, and the part o of the wire proceeds horizontally to the left a short distance, and is bent at right angles downward to form the part o² of the handle, which at its lower end is bent abruptly 70 and folded on itself at o³, forming the loop o⁴, which passes partly around the horizontal arm d of the main right-angular frame A, and pivoting the handle at that point to the main frame A. The part o⁵ of the handle passes 75 upwardly from the loop o⁴, and is bent horizontally, forming the part o⁶, which at its right-hand end is bent vertically downward, forming the part o⁷, the lower end of the part o⁶ being formed into a loop, o⁸, partly surrounding the 80 horizontal bar d of the frame A. The part o⁹ of the wire is then bent upon the part o⁶ and proceeds a short distance upwardly, when it is again bent horizontally to the left, forming the part o¹⁰ of the wire, which at its inner end is 85 bent vertically downward, forming the part o¹¹, which passes through the hook o' in the wire, and is finally bent outwardly and under the arm d of the frame A to form the rack R, the corrugations of which are adapted to engage 90 with the loop l of the spring-frame B.

p represents a spring coiled around the lower part of the handle and around the upper cross-bar, d, of the frame A, and thence projecting forward, and provided with a loop or loops, p', 95 at its forward end, adapted to engage with the forward end of the wire forming the rack R. The tension of the spring p is exerted upwardly, and when its loop p' is passed over the end of the rack it forces the rack R upwardly, 100 and holds the rack in engagement with the loop l in the horizontal upper part, k, of the spring-

frame B. When it is desired to remove the package or books from the carrier, the spring p is pressed downward, so as to release its loop p' from the outer end of the rack, and the 5 spring-frame B is moved outwardly, so that the package or books can be readily removed from the carrier.

Having thus described my invention, what I claim as new, and desire to secure by Letters 10 Patent, is—

1. The combination of the right-angular frame A, spring-frame B, pivoted thereto, handle C, hinged to the upper cross-piece of the frame A, and provided with the rack R, and 15 means adapted to hold the rack in engagement with the frame B, substantially as shown and described.

2. The combination, with the right-angular frame A, made of a single piece of wire, of the 20 spring-frame B, made of a single piece of wire, hinged at its lower end to the frame A, and provided at its upper end with the loop l, handle C, and rack R, both made of one piece of wire and pivoted to the upper end of the 25 main frame A, and spring p, provided at its

outer end with the loop p', substantially as shown and described.

3. In a package and book holder, the combination, with the right-angular frame A, made of a single piece of wire, of the handle C and 30 rack R, both made of a single piece of wire and pivoted to the upper end of the right-angular frame A, substantially as shown and described.

4. The combination, with the right-angular frame A, made of a single piece of wire, and 35 provided with loops b, of the pivoted spring-frame B, made of a single piece of wire, and having hooks i i at its lower ends, which engage with loops b, and its longitudinal sides g curved inwardly, and beveled cross-piece m, 40 adjustably secured to the longitudinal wires g g, substantially as shown and described.

5. In a package and book holder, the handle C and rack R, both made of a single piece of wire, constructed substantially as shown 45 and described.

CHARLES HUFF.
